United States Patent Office

Des. 224,184
Patented July 11, 1972

224,184

BOOT

Dorothy A. Straub and Astrid Morris, both of 19 Center St., Westport, Conn. 06880

Filed Mar. 16, 1971, Ser. No. 125,014

Term of patent 14 years

Int. Cl. D2—04

U.S. Cl. D2—273

Fig. 3

Fig. 1

Fig. 4

Fig. 2

Fig. 5

FIG. 1 is a perspective view of a boot showing our new design;

FIG. 2 is a side elevational view of the boot shown in FIG. 1, the opposite side being of similar appearance;

FIG. 3 is a rear elevational view of the boot shown in FIG. 1;

FIG. 4 is a front elevational view of the boot shown in FIG. 1; and

FIG. 5 is a plan view of the boot shown in FIG. 1.

We claim:

The ornamental design for a boot, as shown and described.
